US00D904405S

(12) **United States Design Patent** (10) **Patent No.:** **US D904,405 S**
(45) **Date of Patent:** **** Dec. 8, 2020**

(54) **PERSONAL COMPUTER**

(71) Applicant: **Michael Ross Catania**, Laurel Springs, NJ (US)

(72) Inventor: **Michael Ross Catania**, Laurel Springs, NJ (US)

(73) Assignee: **Michael Ross Catania**, Laurel Springs, NJ (US)

(**) Term: **15 Years**

(21) Appl. No.: **29/669,740**

(22) Filed: **Nov. 10, 2018**

(51) **LOC (12) Cl.** **14-02**

(52) **U.S. Cl.**

USPC **D14/374**

(58) **Field of Classification Search**

USPC D14/336, 337, 341, 375, 376, 377, 127,
D14/128, 129, 371, 372, 373, 374, 126

CPC G06F 1/1601; G06F 1/1605; G06F 1/162

(57) **CLAIM**

The ornamental design for a personal computer, as shown and described.

DESCRIPTION

FIG. 1 is a front perspective view of a personal computer showing my new design;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front perspective view of a personal computer in an alternate position setting;

FIG. 9 is a front elevational view thereof;

FIG. 10 is a back elevational view thereof;

FIG. 11 is a left elevational view thereof;

FIG. 12 is a right elevational view thereof;

FIG. 13 is a top plan view thereof;

FIG. 14 is a bottom plan view thereof;

FIG. 15 is a front perspective view of a personal computer in the closed position;

FIG. 16 is a front elevational view thereof;

FIG. 17 is a back elevational view thereof;

FIG. 18 is a left elevational view thereof;

FIG. 19 is a right elevational view thereof;

FIG. 20 is a top plan view thereof; and,

FIG. 21 is a bottom plan view.
